UNITED STATES PATENT OFFICE

FRANK ZAHORIK, OF RACINE, WISCONSIN

GOLF BAG SUPPORTING DEVICE

Application filed May 16, 1932. Serial No. 611,588.

My invention relates to a device for supporting a golf bag so that the bag may be conveniently stood in a diagonal position without manual support.

5 An important object of my invention is the provision of a simple, inexpensive device which is quickly and conveniently attachable to standard golf bags of various sizes and which has a pair of pivoted legs and conveniently operable means for throwing the same into operative position when it is desired to set the golf bag down.

10 A further object of my invention is the provision of a golf bag accessory which is adapted to be mounted about the upper end of a bag, and which has means thereon mounted a short distance above the usual handle of the golf bag which is actuatable by the thumb of the hand gripping the bag to cause legs pivoted on said device to be thrown outwardly in a projecting position.

15 A further important object of my invention is the provision of a golf bag support having a pair of pivoted legs which are adjustable so as to fit various size bags and which has an adjustable means to mount the same on bags having their handles at varying distances from the upper periphery of the golf bag, in which the means for manually swinging the legs outwardly from the bag to supporting position are normally locked in a position wherein the legs are adjacent the bag, and in which spring means are provided to cause the legs to be automatically 20 returned to non-operating position when the bag is raised and the legs lose contact with the ground.

25 Other and further important objects of this invention will be apparent from the disclosures in the specification and the accompanying drawing.

30 This invention (in a preferred form) is illustrated in the drawing and hereinafter more fully described.

35 On the drawing:

36 Fig. 1 is a side elevational view of my golf bag supporting device showing the position in which it is adapted to be mounted on a golf bag which is partially indicated by dotted lines.

Fig. 2 is a fragmentary view taken from the inside of my device looking at the curved surface thereof which adjoins the golf bag.

Fig. 3 is a top plan view of my device showing the relative position of the parts as 55 viewed.

Fig. 4 is a side elevational view showing my device mounted on a golf bag shown in dotted lines.

Fig. 5 is a cross sectional view of a fragment of my device taken on line V—V of Fig. 3.

As shown on the drawing:

60 The reference numeral 10 indicates a golf bag of the usual construction having a rolled upper peripheral bead and a handle 11 secured to the side thereof in the usual position a short distance from the upper periphery. 65 12 indicates a sheet metal arcuate shell which is adapted to snugly fit a portion of the distance around the bag. Arcuate metal straps 13 and 14 each have one end thereof secured to the end of the shell 12 as indicated in Figs. 2 and 3, one of said straps 13 having a plurality of spaced apart apertures which are 70 adapted to be engaged by an inwardly projecting stud 15 which is formed integral with a bracket 16 secured by a screw to a bracket 17, which in turn is permanently secured on the outer surface of the strap 14. The means 75 just described provides adjustability of my device whereby the same may be mounted to fit golf bags of varying circumferences.

80 The central rectangular portion of the front of the shell 12 is pressed outwardly to form a boss, said boss maintaining substantially the same degree of curvature as the shell. As indicated in Figs. 1, 3 and 5, a substantially rectangular curved guide plate 18 85 which is of a size slightly larger than the boss just described is secured by rivets 19 to said boss so that the sides thereof are in vertical position and parallel to the longitudinal axis of the golf bag. A slidable mounting plate 20, having a pair of upper outwardly extending offset ears 21 and 22 and smaller integral apertured ears 23 and 24, is slidably mounted upon and over said guide plate 18 by means of a pair of hooked members 25 and 26 which 90 are secured by welding or the like to the mov- 95

able mounting plate 20 and which slidably engage the side edges of the guide plate 18 as indicated in Fig. 3. A comparatively large rectangular aperture is punched in the center 5 of the mounting plate 20 in such a manner so that integral L-shaped ears 27 and 28 will be formed at the sides of said rectangular apertures, said ears being bent substantially perpendicular to the plate and for a purpose 10 which will now be described.

Each of the central integral ears 27 and 28 has an aperture at its lower extremity in which is removably secured a pivot bolt 29 on which is pivoted a short lever 30, as clearly shown in Fig. 5. A substantially right-angled, manually operable lever 31 has one end thereof secured by screws upon and adjacent the outer surface of the lever 30 in a position so that one portion thereof will be substantially perpendicular to the shell 12 and mounting plate 20. A stud 32 is formed on the inside surface of the short lever 30 as indicated in Fig. 5, which is adapted to seat in apertures 33 formed in registry with each 20 other in the guide plate 18 and bossed portions of the shell 12. The aperture 33 is formed at such a point in said guide plate and shell so that the stud 32 will seat therein when the mounting plate 20 is at its uppermost position.

Mounted in suitable apertures formed in the upper projecting extremity of the ears 27 and 28 is a bolt about which is mounted a wire coil spring 34, the end of which is adapted to normally press against the surface of the lever 31 to normally cause the stud 32 to remain in the apertures 33, in which position the legs hereinafter described are restricted adjacent the golf bag. It will be apparent 35 that it is necessary to press the lever 31 toward the handle of the golf bag to cause the stud to disengage the aperture to permit the downward slidable movement of the mounting plate 20 and attached parts to, in turn, 40 cause the legs hereinafter described to be placed into operative supporting position.

A pair of bell-crank legs 35 and 36 are pivoted to radially projecting studs 38 on opposite sides of the shell 12 and which are formed 50 at points less than 180° apart and at equal distances from the respective ears 21 and 22. The upper ends of said bell-crank legs 36 and 37 are pivoted by means of suitable studs in horizontally extending slots in the ears 21 and 22 of the shell 20. As indicated in Figs. 2 and 3, the lower portion of the opposite ends 55 of the shell 12 are formed substantially flat and in a tangential outwardly extending direction. Arcuate slots 39 and 40 are formed 60 respectively in the flat plane surface of the shell 12 with the studs 38 as respective axes for said slots. Bolts 41 and 42 pass through and are slidably respectively in the slots 39 and 40, and pass through and are secured in 65 suitable apertures in the bell-crank legs 36

and 37 respectively. It will be apparent that as the legs 36 and 37 are manually caused to be extended outwardly by downward movement of the plate 20, said legs will be projected in an outward spaced apart direction 70 due to the guiding action of the slots 39 and 40 in the respective outwardly extending end portions of the shell 12. When in an outwardly extending position the ground engaging ends of the legs will be nearly twice as 75 far from each other as the diameter of the golf bag, thereby preventing tipping over of the bag under any circumstances.

A very important feature of my invention 80 comprises the means to automatically return the legs to restricted position adjacent the golf bag when the golf bag is picked up by its normal handle. Said means comprises a pair of coil springs 43 and 44 which have one end secured in the 85 lower apertures 23 and 24 of the mounting plate 20 and their other ends secured to respective hooks formed on the lower ends of clips 45 and 46 respectively, each of which are secured by suitable rivets to the upper 90 edge of the shell 12. Said clips are hook-shaped and adapted to assist in holding my device in proper position adjacent to the upper periphery of the golf bag. The springs 43 and 44 normally hold the mounting plate 20 in its uppermost position with the legs 36 and 37 in operative position adjacent to the 95 golf bag and operate to automatically restrict said legs upon manual lifting of the golf bag to carry it away. When it is desired to set the bag down the hand of the carrier, gripping the usual handle of the bag, need only to extend his thumb to press upon the extended portion of the lever 31 to cause 100 outward movement of the levers 30 and 31 to disengage said stud from its seat, and the usual downward pressing movement of said thumb will slide the mounting plate 20 toward the carrier's hand to cause said legs to be projected outwardly in the manner described and thereupon the bag is set down to engage the legs upon the ground.

I am aware that many changes may be made and numerous details of the invention and construction thereof may be varied 105 through a wide range without departing from the principles of this invention, and I therefore do not desire to limit the patent granted thereon otherwise than necessitated by the prior art.

I claim as my invention:

1. A golf bag supporting device comprising 110 an arcuate shell; means to adjustably and removably secure said shell about a golf bag, said shell having end portions formed to present inclined plane surfaces on opposite sides of said shell and said surfaces having arcuate 115 slots therein; a mounting plate slidably mounted for vertical movement on the outer surface of said shell; transversely extending 120

- slotted ears formed integral with the opposite sides of said slidable mounting plate; legs having bell-crank arms pivoted on substantially opposite sides of said shell, the ends of 5 said arms being respectively pivoted in said ear slots; a bolt secured in each of said legs and slidably engaging said slots in said plane surfaces whereby the legs are guided in projection and retraction thereof, and whereby 10 said legs are held rigid; and a plurality of springs connecting said slidable mounting plate and upper peripheries of said shell adapted to normally hold said mounting plate in upper position and said legs in retracted 15 position.
2. A golf bag supporting device comprising an arcuate shell; means to adjustably and removably secure said shell about a golf bag, said shell having end portions formed to present inclined plane surfaces on opposite sides of said shell and said surfaces having arcuate slots therein; a mounting plate slidably mounted for vertical movement on the outer surface of said shell; transversely extending 20 slotted ears formed integral with the opposite sides of said slidable mounting plate; legs having bell-crank arms pivoted on substantially opposite sides of said shell, the ends of 25 said arms being respectively pivoted in said ear slots; a bolt secured in each of said legs and slidably engaging said slots in said plane surfaces whereby the legs are guided in projection and retraction thereof, and whereby 30 said legs are held rigid; a plurality of springs connecting said slidable mounting plate and upper peripheries of said shell adapted to normally hold said mounting plate in upper position and said legs in retracted 35 position.
3. A golf bag supporting device comprising an arcuate shell; means to adjustably and removably secure said shell about a golf bag, said shell having end portions formed to present inclined plane surfaces on opposite sides of said shell and said surfaces having arcuate slots therein; a mounting plate slidably mounted for vertical movement on the outer surface of said shell; transversely extending 40 slotted ears formed integral with the opposite sides of said slidable mounting plate; legs having bell-crank arms pivoted on substantially opposite sides of said shell, the ends of 45 said arms being respectively pivoted in said ear slots; a bolt secured in each of said legs and slidably engaging said slots in said plane surfaces whereby the legs are guided in projection and retraction thereof, and whereby 50 said legs are held rigid; a plurality of springs connecting said slidable mounting plate and upper peripheries of said shell adapted to normally hold said mounting plate in upper position and said legs in retracted 55 position.
4. A golf bag stand comprising a semi-cylindrical shell having a central aperture and the ends of which terminate in outwardly inclined plane surfaces; said surfaces having arcuate slots therein; a pair of adjustable straps connected to the ends of said shell and adapted to secure the same about a golf bag; a mounting plate slidably mounted for vertical movement on the forward face of said shell and terminating in transversely extending slotted ears, said plate having a relatively 60 large central aperture; a manually operable lever pivotally mounted on the forward face of said mounting plate; a stud on the under side of said lever adapted to seat in said central shell aperture to releasably secure said mounting plate in upper position; a pair of legs having bell-crank arms pivoted on opposite sides of said shell, and the ends of said bell-crank arms pivotally engaging said ear slots; a bolt in each of said legs and engaging 65 said shell slots respectively whereby said legs will be guided in projection and retraction; and a plurality of springs connected at one end to said mounting plate and at their other ends to the upper periphery of said shell, said springs being adapted to automatically return said legs to retracted position and said 70 slidable mounting plate to uppermost position.
5. A golf bag stand comprising a semi-cylindrical shell having a central aperture and the ends of which terminate in outwardly inclined plane surfaces; said surfaces having arcuate slots therein; a pair of adjustable straps connected to the ends of said shell and adapted to secure the same about a golf bag; a mounting plate slidably mounted for vertical movement on the forward face of said shell and terminating in transversely extending slotted ears, said plate having a relatively 75 large central aperture; a manually operable lever pivotally mounted on the forward face of said mounting plate; a stud on the under side of said lever adapted to seat in said central shell aperture to releasably secure said mounting plate in upper position; a pair of legs having bell-crank arms pivoted on opposite sides of said shell, and the ends of said bell-crank arms pivotally engaging said ear slots; a bolt in each of said legs and engaging 80 said shell slots respectively whereby said legs will be guided in projection and retraction; and a plurality of springs connected at one end to said mounting plate and at their other ends to the upper periphery of said shell, said springs being adapted to automatically return said legs to retracted position and said 85 slidable mounting plate to uppermost position.
6. A golf bag stand comprising a semi-cylindrical shell having a central aperture and the ends of which terminate in outwardly inclined plane surfaces; said surfaces having arcuate slots therein; a pair of adjustable straps connected to the ends of said shell and adapted to secure the same about a golf bag; a mounting plate slidably mounted for vertical movement on the forward face of said shell and terminating in transversely extending slotted ears, said plate having a relatively 90 large central aperture; a manually operable lever pivotally mounted on the forward face of said mounting plate; a stud on the under side of said lever adapted to seat in said central shell aperture to releasably secure said mounting plate in upper position; a pair of legs having bell-crank arms pivoted on opposite sides of said shell, and the ends of said bell-crank arms pivotally engaging said ear slots; a bolt in each of said legs and engaging 95 said shell slots respectively whereby said legs will be guided in projection and retraction; and a plurality of springs connected at one end to said mounting plate and at their other ends to the upper periphery of said shell, said springs being adapted to automatically return said legs to retracted position and said 100 slidable mounting plate to uppermost position.
7. A golf bag stand comprising a semi-cylindrical shell having a central aperture and the ends of which terminate in outwardly inclined plane surfaces; said surfaces having arcuate slots therein; a pair of adjustable straps connected to the ends of said shell and adapted to secure the same about a golf bag; a mounting plate slidably mounted for vertical movement on the forward face of said shell and terminating in transversely extending slotted ears, said plate having a relatively 105 large central aperture; a manually operable lever pivotally mounted on the forward face of said mounting plate; a stud on the under side of said lever adapted to seat in said central shell aperture to releasably secure said mounting plate in upper position; a pair of legs having bell-crank arms pivoted on opposite sides of said shell, and the ends of said bell-crank arms pivotally engaging said ear slots; a bolt in each of said legs and engaging 110 said shell slots respectively whereby said legs will be guided in projection and retraction; and a plurality of springs connected at one end to said mounting plate and at their other ends to the upper periphery of said shell, said springs being adapted to automatically return said legs to retracted position and said 115 slidable mounting plate to uppermost position.
8. A golf bag stand comprising a semi-cylindrical shell having a central aperture and the ends of which terminate in outwardly inclined plane surfaces; said surfaces having arcuate slots therein; a pair of adjustable straps connected to the ends of said shell and adapted to secure the same about a golf bag; a mounting plate slidably mounted for vertical movement on the forward face of said shell and terminating in transversely extending slotted ears, said plate having a relatively 120 large central aperture; a manually operable lever pivotally mounted on the forward face of said mounting plate; a stud on the under side of said lever adapted to seat in said central shell aperture to releasably secure said mounting plate in upper position; a pair of legs having bell-crank arms pivoted on opposite sides of said shell, and the ends of said bell-crank arms pivotally engaging said ear slots; a bolt in each of said legs and engaging 125 said shell slots respectively whereby said legs will be guided in projection and retraction; and a plurality of springs connected at one end to said mounting plate and at their other ends to the upper periphery of said shell, said springs being adapted to automatically return said legs to retracted position and said slidable mounting plate to uppermost position; and adjustable mounting means whereby said shell may be secured 130

to a golf bag handle comprising a downwardly extending slotted tongue on the lower periphery of said ear; a bifurcated arm secured adjacent said tongue, and a screw threadingly engaging said arm and frictionally engaging said slot.

6. A golf bag stand comprising a curved shell having a central aperture and the ends of which terminate in outwardly inclined slotted plane surfaces; adjustable means secured to said shell adapted to removably secure the same about a golf bag; a guide member secured on the front of said shell; a mounting plate slidably mounted on said guide member and terminating in transversely extending slotted ears, said plate having a relatively large central aperture; a manually operable lever pivotally mounted on the forward face of said mounting plate; a stud on the under side of said lever adapted to seat in said central shell aperture to releasably secure said mounting plate against sliding movement; a pair of legs having bell-crank arms pivoted on opposite sides of said shell, and the ends of said bell-crank arms pivotally engaging said ear slots; a bolt in each of said legs and slidably engaging said shell slots respectively whereby said legs will be guided in projection and retraction; and spring means adapted to automatically return said legs to retracted position and said slidable mounting plate to uppermost position.

7. A golf bag stand comprising an arcuate shell; adjustable means to removably secure the same about a golf bag; a plate slidably mounted on said shell and having side apertures; a manually operable lever pivoted upon the face of said plate; spring means mounted adjacent said lever adapted to normally hold the lever in locking position; a locking stud on said lever adapted to removably lock said plate in a predetermined position; and a pair of legs having bell-crank arms pivoted on opposite sides of said shell, the ends of said bell-crank arms pivotally engaging the apertures in said slidable plate, the downward movement of said plate being adapted to project said legs outwardly.

50. In testimony whereof I have hereunto set my hand this 7th day of May, 1931, in Chicago, Cook County, Illinois.

FRANK ZAHORIK.
